UNITED STATES PATENT OFFICE.

EMIL CHRISTENSEN, OF PORTLAND, OREGON.

SAW FILING AND SETTING MACHINE.

SPECIFICATION forming part of Letters Patent No. 472,031, dated April 5, 1892.

Application filed January 15, 1892. Serial No. 418,174. (No model.)

To all whom it may concern:

Be it known that I, EMIL CHRISTENSEN, a citizen of the United States, residing at Portland, in the county of Multnomah, State of Oregon, have invented certain new and useful Improvements in a Combined Saw Filing and Setting Machine, of which the following is a specification, reference being had therein to the accompanying drawings.

This invention relates to that class of saw-sharpening machines in which the file is suitably reciprocated against the saw-teeth; and the objects of my improvement are to provide simple means for reciprocating the file and also for operating the saw-setting mechanism and adjust them to file and set the teeth of a band-saw without displacing it from the wheels by which it is carried. I attain these objects by the construction illustrated in the accompanying drawings, in which—

Figure 1 is a side view of a combined saw-sharpening and saw-setting machine constructed in accordance with my invention. Fig. 2 is a top view of the same. Fig. 3 is an end view of the same. Fig. 4 is a side view of the operating-lever to rock the file. Fig. 5 is a perspective of the saw-feeding lever. Fig. 6 represents on a larger scale a side view of the saw-setting mechanism. Fig. 7 is a top view of the same with its cap-plate removed. Fig. 8 is a top view of the cap-plate removed from Fig. 7. Fig. 9 is a top view of the operative lever of the saw-clamping jaws. Fig. 10 is a perspective view of the pivoted finger forming part of the saw-setting carriage. Fig. 11 is a vertical section of one of the file-clamps.

In said drawings, A represents the base-plate of the machine, having projecting upward therefrom the bearings A², that receive the driving-shaft B, through which motion is given to all the movable parts of the machine, said shaft having at one end a hand-crank B'. The shaft can also be operated by means of a belt or band in connection with a grooved pulley mounted thereon. Upon one end of said shaft is mounted one end of a cam B², that has one of its faces preferably recessed and is rotated in the direction of the arrow thereon. This cam is united to a horizontally-sliding shaft C by means of a connecting-rod c, having one end carrying a bolt adjust-

ably retained in a radial slot in the cam and the other end loosely attached to the shaft C by means of a screw c² entering the side of 55 said shaft after passing loosely through a bearing-hole in one end of said rod, a small amount of loose fitting being necessary to permit the shaft C to be partly rotated or oscillated in its bearings A³ while it is reciprocated through them. The bearings A³ project vertically from the top of base-plate A, but at a suitable distance apart to permit the shaft C to carry between them the clamps c³ c⁴, by which the file d is retained connected 60 to said shaft C. Each file-clamp is provided with a screw c⁵ on top thereof, the point of which enters a groove c⁶, made lengthwise of the shaft C to control the rocking of said shaft and of the file. The clamp c⁴ is provided 65 with a laterally-extended arm or lever C⁴, that is normally kept in a horizontal position by a weight C⁵, placed adjustably thereon, said weight carrying a screw on one side, by which it is screwed to the lever C⁴. To prevent the outer end of said lever from being depressed below a substantially horizontal position, said end rests upon a guard D, projecting from the top of the base-plate A. The top 75 of said guard is horizontal, and upon it the 70 outer end of said lever C⁴ is adapted to travel; but as said outer end is provided with an adjusting-screw c⁷ the flat point of said screw will travel upon the guard D if it projects beyond the bottom surface of the lever C⁴. To steady 80 the movements of the lever C⁴ and prevent it from being jerked up too high by the momentum of the operating-lever E when the machine is operated by a high speed, a spring f is used which has tendency to depress the lever C⁴. For this purpose one end of said spring 85 is coiled around and secured to the support F of the lever E, and the opposite end is made to pass through an eye f², pendent from the under side of the lever C⁴. The operating-lever E is pivoted at e in the upper end of the support F, and the latter projects up from the top of the base-plate A. One end of said lever 90 is made to bear against the periphery of the cam B² and is operated by the latter. The opposite end of the lever E bears against the under side of the lever C⁴ to elevate the latter and partially rotate the shaft C, and consequently take the file away from the saw 95 100

during the rearward stroke of said file. At the same time the saw S is elevated one tooth by a pawl g, pivoted to the lever G, that has one end in engagement with a hook E², formed 5 on the under side of the lever E. The lever G carries a small spring g² to keep the pawl g in engagement with the teeth of the saw. Said lever is mounted upon a fulcrum pin or bolt G², that is secured to a standard A⁴, projecting up from the base-plate A and beyond 10 one of its sides. The lever G has in its outer end a series of holes g³ to receive in either one of them the fulcrum-bolt g², adapted to be received in one of the corresponding holes 15 in the standard A⁴ to give more or less vertical oscillation to the lever carrying the saw-feeding pawl g. The saw is guided and maintained against one side of the standard A⁴ by a retaining-plate A⁵, which is provided with a 20 feather entering a groove a⁴ in the side of the said standard, vertical grooves of different depths in each end to receive different-sized saws, and a bolt or bolts secured to the standard and passing through slots a⁵ in the plate 25 A⁵, so that said plate can be reversed for different-sized saws.

When the parts are in the position shown in Figs. 1, 2, and 3, the lever C⁴, having the shaft C for fulcrum, is lowered upon its guide 30 D and the saw-tooth receives one stroke from the file, the adjustable weight C⁵ on said lever giving the desired pressure of the file against the saw. Said file is retained at each end by latches c⁸, Fig. 11. Each latch, being pivoted 35 in a groove of the clamp, has a screw c⁹ bearing against its lower half to force its upper half against the file and firmly clamp the latter.

To do the setting of the saw-teeth, the connecting-rod H of the saw-set is subjected to 40 four motions, two of which for each revolution of the cam B² to set one of the teeth to one side and the succeeding tooth to the opposite side. For this purpose one end of connecting-rod is secured to a horizontally-sliding carriage operated by said cam. Said carriage consists of two horizontal rods K, made to pass through a standard A⁶, projecting from the base-plate, and through eyes or bearings 45 (not shown) projecting from the side of the main-shaft bearing A⁷. A single rod K may be used for the same purpose by providing it with a groove to receive a feather that would prevent it from rotating. The rods K are 50 one above the other at suitable distance apart, and are connected together near one end by a clamp L and at the other end by a clamp M, having on top thereof a funnel-shaped guide M², open on one side. This 55 clamp has also at its lower end a foot M³, to which one end of the connecting-rod H is pivoted at m.

The cam B² has projecting from its side a roller b², that imparts the four motions to the carriage and to the connecting-rod H as follows: The rods K and their clamps L and M are shown in the drawings to the extreme

left of their course. The cam B² being made to rotate in the direction of the arrow thereon, the roller b² moves down the funnel-shaped 70 guide M² and causes the rods K, attached thereto, to move a certain distance to the right side. The roller continues to advance, passes on the outside, and presses against said outside of a wedge-shaped, but curved, finger L², 75 pivoted at l to the under side of the clamp L, near the top thereof. This finger is retained by its pivot with sufficient friction against the clamp L to remain temporarily at any angle that it may be pushed by the roller b². The 80 amount of tilting or inclination that the finger L² can have is small, as it is limited by a pin l², projecting from its side and abutting against the ends of a small horizontal slot in the side of the clamp L, in which said pin is received. 85 As above stated, the roller b² presses against the outside of the finger L² and moves the rods K, with their clamps L M, to the extreme right of their course. When the roller b² has passed the fulcrum-pin l, it presses against the wide 90 portion of the finger L², and thus tilts the point of the finger down or toward the periphery of the cam B². The roller b², continuing to advance, again enters the funnel-shaped 95 guide M² and moves it and the rods K half-way to the left. The roller b², continuing to advance, bears against the inside of the finger L² and causes the rods K to move to the extreme left. The roller b², passing the fulcrum of the finger L², again throws the point 100 of the finger to the position shown in Figs. 1 and 2.

The saw-set consists of a narrow steel plate P, that is secured at one end to the base-plate A of the machine by means of a bolt or screw p, and at the other end is retained adjustably depressed by means of a thumb-screw p², the point of which enters a lug a on the side of the base-plate A. The plate P, being of cast-steel, has the desired resilience to be adjusted 105 up or down in relation to the saws, some of which have three teeth and others have five teeth to the inch, the adjustment being made relative to the pawl g. To the plate P and its cap-plate P² are pivoted at p³ the jaws Q, 110 used to clamp the saw while its teeth are bent or set to either side. Said jaws are made to clamp the saw by spreading their long straight ends by means of a lever R, pivoted between them at r to the plate P and its cap-plate. 115 Said lever has an eccentric-head having two of its edges flattened to relieve the jaws of pressure when the lever is on a line with the axis of the jaws; but when turned to either side, as shown in Fig. 7, the saw is clamped 120 properly to have its teeth set. The outer end of the lever R is connected by means of a link R² with the set-lever T, that has its inner end pivoted at t to the plate P and its cap-plate P². The set lever has its outer end provided 125 with the holes t² to receive in either one of them a bolt or pin t², projecting from the under side of the reciprocating connecting-rod H. When said rod is connected with the in-

ner hole, as shown in the drawings, more throw is given to the lever, and consequently more set to the saw. The four motions imparted to the saw-set by the roller b^2 on the cam B^2 , in connection with the funnel-guide M^2 and the pivoted finger L^2 , will set one tooth to one side and then return to the central position to allow one tooth of the saw to pass. Then it will set one tooth on the opposite side and return to the center again, &c.

To connect the machine to the band-saw table, two bolts or dowels can be used and inserted in the holes V , formed in the ends of the base-plate and made to enter corresponding holes in the saw-table. The machine can also be set in any suitable location and be operated by a belt passing around the pulley U on the main shaft.

Having now fully described my invention,

20 I claim—

1. In a saw-filing machine, the combination of a cam and its shaft, a reciprocating shaft C and connecting-rod uniting it to the cam, file-clamps adjustably secured to the shaft C , one of said clamps being a lever C^4 , a weight adjustably secured upon said lever, and means for lifting the lever C^4 , and a guide D , substantially as described.

2. The combination of a cam and its shaft, a reciprocating shaft C and connecting-rod uniting it to the cam, file-clamps adjustably secured to the shaft C , one of said clamps being a lever C^4 , and a pivoted lever E , having one end in contact with the cam and the opposite in contact with the under side of the lever C^4 , substantially as described.

3. The combination of a cam and its shaft, a reciprocating shaft C and connecting-rod uniting it to the cam, file-clamps adjustably secured to the shaft C , one of said clamps having a lever C^4 , a pivoted lever E , having one end in contact with the under side of the lever C^4 , and a spring f , having one end in engagement with said lever C^4 , substantially as described.

4. The combination of a cam and its shaft, a reciprocating shaft C and connecting-rod uniting it to the cam, a pivoted lever having a hook on the under side thereof, a lever G in engagement with said hook, and a pawl upon said lever G , substantially as described.

5. The combination of a cam and its shaft, a reciprocating shaft C and connecting-rod uniting it to the cam, and file-clamps adjustably secured to the shaft C , each clamp being grooved and having a pivoted latch in the groove and a screw bearing against its lower half, substantially as described.

6. The combination of a cam and its shaft and a roller b^2 on said cam with a horizontally-reciprocating carriage having a funnel M^2 clamped thereon at one end, a clamp L at the opposite end, and a finger L^2 , pivoted to the clamp L , substantially as described.

7. The combination of a cam and its shaft and a roller b^2 on said cam, a reciprocating carriage having a funnel M^2 at one end, a clamp L at the opposite end, and a finger L^2 , pivoted to the clamp L , with a connecting-rod H , a plate P , adjustably secured to its support, a pair of jaws pivoted to the plate P , a pivoted lever R to close said jaws and a saw-set lever T pivoted between said jaws, and a link uniting the levers R and T , substantially as described.

8. In combination with a saw-filing machine, a circularly-traveling roller b^2 mounted thereon, and a reciprocating carriage having a funnel-shaped guide at one end and a pivoted finger at the other end operated by said roller, whereby four distinct reciprocating motions are given to said carriage, substantially as described.

In testimony whereof I affix my signature in presence of two witnesses.

EMIL CHRISTENSEN.
